(57) **CLAIM**

The ornamental design for an electric actuator, as shown and described.

DESCRIPTION

1. Electric actuator

1.1 : top, in front right perspective

1.2 : top, in front perspective

1.3 : top, in front left perspective

1.4 : bottom, in rear left perspective

1.5 : bottom, in rear perspective

1.6 : bottom, in rear right perspective

This is an actuator used for moving the pointer of a dashboard indicator.
